UNITED STATES PATENT OFFICE.

HENRY H. VAUGHAN, OF MONTREAL, QUEBEC, CANADA.

LATERAL-MOTION DEVICE FOR RAILWAY-TRUCKS.

1,099,891.

Specification of Letters Patent.

Patented June 9, 1914.

Application filed September 22, 1913. Serial No. 791,062.

To all whom it may concern:

Be it known that I, HENRY H. VAUGHAN, a citizen of the United States, residing at Montreal, in the county of Hochelaga, Province of Quebec, Canada, have invented certain new and useful Improvements in Lateral-Motion Devices for Railway-Trucks; and I do hereby declare the following to be a full, clear, and exact description of the invention, such as will enable others skilled in the art to which it appertains to make and use the same.

My present invention has for its object to provide a simple and efficient lateral motion device for railway trucks; and to such ends, generally stated, the invention consists of the novel devices and combinations of devices hereinafter described and defined in the claims.

This application is in the nature of an improvement on, or modification of the lateral motion device disclosed and claimed in my co-pending application, Serial Number 791,061, filed of date, September 22, 1913, and entitled "Lateral motion device for railway trucks." In my said co-pending application, the said lateral motion devices involve opposed wedge plates, so-called, having reversely inclined oblique surfaces for direct frictional engagement. In practice, this direct frictional engagement between the oblique surfaces of the wedge plates was found to give the desired normal stability, that is, resistance against lateral movements of the truck body, in respect to the truck wheels, combined with a frictional yielding action serving to prevent excessive pressure of the wheel flanges against the rails under considerable lateral stress, such, for instance, as produced in traveling curves at high speed. However, for some purposes, or in some applications of this frictional lateral motion device, it has been found that too great frictional resistance to lateral movements of the truck body, in respect to the truck wheels, results, when the entire load is carried on the directly engaging frictional surfaces of the opposed wedge plates. To reduce the friction in such lateral motion devices I combine anti-friction rollers or elements and coöperating diverging roller engaging surfaces, with directly engaging inclined or converging frictional surfaces of the wedge plates.

In the accompanying drawings which illustrate the invention, like characters indicate like parts throughout the several views.

Referring to the drawings: Figure 1 is a fragmentary view in side elevation, with some parts broken away and with some parts sectioned, showing one of my improved lateral motion devices applied to a tender truck; Fig. 2 is a transverse vertical section taken on the line $x^2 x^2$ on Fig. 1; Fig. 3 is a plan view of certain of the parts shown in Fig. 1, some parts being removed; Fig. 4 is a perspective view showing one of the wedge plates of the lateral motion device; Fig. 5 is a view chiefly in side elevation, but with some parts sectioned and some parts broken away, showing my improved lateral motion device applied between the side frame and truck bolster of a car; and Fig. 6 is a transverse vertical section taken approximately on the line $x^6 x^6$ on Fig. 5.

Referring first to the construction illustrated in Figs. 1 to 4, inclusive, which illustrate the improved lateral motion device applied to a tender truck, the numeral 1 indicates the journal box, the numeral 2 the journal box pedestals, the numeral 3 the top bar of the truck side frame, and the numeral 4 the equalizer or equalizing bars. The journal boxes 1 are mounted for vertical movements but allowed a restricted amount of lateral movement, in respect to the pedestals 2, between which they work. The top bars 3 are rigidly secured to the upper ends of the pedestals 2 by nut-equipped bolts 5, or other means. The equalizing bars 4 support the truck springs in the usual, or any suitable way, not shown. Usually, they are arranged in pairs and seated at their ends on the top of the journal boxes. In the present instance, however, my improved lateral motion devices are interposed between the journal boxes and the ends of the said equalizing bars, and each such lateral motion device, comprises a lower wedge plate 6 and an upper wedge plate 7, the former of which, as shown, are anchored on the tops of the journal boxes, by means of dowel pins 7^a, and the latter of which are provided with top channels in which the ends of the equalizing bars 4 are seated and held against lateral movement with respect to the pedestals 2. The so-

called wedge plates 6 and 7 are formed with upwardly diverging frictional surfaces 8 that are in direct engagement. The upper wedge plate 7 is formed on its under side with downwardly diverging roller engaging surfaces 9 and the lower wedge plate 6 is formed with upwardly diverging roller engaging surfaces 10. The surfaces 8, 9 and 10 all have the same degree of deviation from a horizontal plane. A bearing roller 11 is interposed between the said surfaces 9 and 10. The roller 11 is held against end-wise displacement, as shown, by retaining strips 11^a, secured to the lower wedge plate 6, at the extremities of the diverging surfaces 10. With this arrangement, as is obvious, the weight of the load transmitted to the upper wedge plate 7, through the equalizing bars 4, and operating through the friction surfaces 8, 9 and 10, and roller 11, will tend to maintain the said wedge plates 6 and 7 in central or intermediate normal positions, shown in Fig. 2. When the truck wheels, journal boxes, and lower wedge plates 6 are moved toward the right, in respect to Fig. 2, the right hand or inside oblique friction surfaces 8 will slide frictionally, one upon the other, and the roller 11 will be rolled between the inner oblique surfaces 10 of the lower plate 6, and the outer oblique surface 9 of the upper wedge plate. The roller will, therefore, very greatly reduce the friction which would otherwise be produced in the lateral motion device. Otherwise stated, the roller and co-operating diverging roller engaging surfaces, work in conjunction with the directly engaging frictional surfaces 8 and carry a very material part of the load and make lateral movement of the truck body, in respect to the truck wheels and journal boxes, freer than where the load is carried entirely on friction surfaces, and at the same time, the desired normal stability is obtained.

In Figs. 5 and 6, there are shown substantially the same wedge plates that are illustrated in Figs. 1 to 4, inclusive, incorporated in or directly associated with a combined lateral and radial motion device that is indirectly interposed between the truck side frame and the body bolster of a car. In this arrangement, the said upper and lower wedge plates, which have the same opposed oblique frictional surfaces and interposed roller, as the bearing plates 6 and 7, are indicated, respectively, by the numerals 12 and 13. Of the parts of the truck shown in said Figs. 5 and 6, the numeral 14 indicate the truck side frames, the numeral 15 the journal boxes, the numeral 16 the transom rigidly connecting the truck side frames, the numeral 17 the car body, the numeral 18 the car body bolster, the numeral 19 the center pivot casting slidably mounted on the transom 16, and the numeral 20, a depending hub cen-

trally secured to the body bolster 18 and mounted for both pivotal and vertical movements in the sliding casting 19. Said parts 14 to 20, just noted, are shown as of the construction disclosed and claimed in the John C. Barber application, Serial Number 760,611, filed of date, April 12th, 1913, entitled "Car trucks." The lower wedge plate 12 is secured on radial motion rollers 21, which, in turn, are mounted to travel on a lower bearing plate 22, shown as riveted to the web of the transom 16 and the flanges of the side frame 14. The rollers 21 run in grooves in the members 12 and 22, so that the said lower wedge plates 12 will partake of the lateral movements of the truck frame. The truck springs 23 are interposed between the upper wedge plate 13 and the body bolster 18, and the wedge plate 13, while free for vertical movements, in respect to the body bolster, is held for movements therewith, transversely of the truck, this, as shown, being accomplished by providing the said wedge plate 13 with upturned end arms 24 (see Fig. 5), that work in vertical guides 25, secured on the side plates of the said body bolster.

The expression "wedge plates" is herein used in a broad sense to include the opposed or co-operating bearing members of the lateral motion device and is not intended to limit these members to flat form nor to elements separate and distinct from other elements. Also, the term "roller" is used in a broad sense to indicate an element interposed between the wedge plates or bearing members and having a rolling or rocking contact therewith, as distinguished from a sliding frictional engagement.

What I claim is:

1. A lateral motion device for railway trucks, comprising opposing bearing plates having directly engaging frictional surfaces and also interposed anti-friction devices, each carrying part of a load.
2. A lateral motion device for railway trucks, comprising opposed wedge plates having oblique friction surfaces in direct engagement, and a roller interposed between said bearing plates and carrying part of the load.
3. A lateral motion device for railway trucks, comprising upper and lower wedge plates formed with directly engaging, reversely inclined friction surfaces and with separated inclined and diverging roller engaging surfaces, and provided with interposed rollers directly engaging the said roller engaging surfaces.
4. In a railway truck, a lateral motion device therefor, comprising upper and lower wedge plates, the former partaking of the lateral movements of the truck body and the latter, of the journal boxes, said wedge plates being formed with directly engaging

reversely inclined friction surfaces, and with separated reversely inclined roller engaging surfaces, the said frictional and roller engaging surfaces having the same incline, and a roller interposed between said wedge plates and directly engaging the said roller engaging surfaces thereof.

In testimony whereof I affix my signature in presence of two witnesses.

HENRY H. VAUGHAN.
